UNITED STATES PATENT OFFICE

110,367

DESIGN FOR A TOBACCO ASH RECEPTACLE

Philip N. Sea, Chicago, Ill.

Application April 23, 1938, Serial No. 76,719

Term of patent 7 years

To all whom it may concern:

Be it known that I, Philip N. Sea, a citizen of the United States, residing at Chicago, in the county of Cook and State of Illinois, have invented a new, original, and ornamental Design for a Tobacco Ash Receptacle, of which the following is a specification, reference being had to the accompanying drawing, forming part thereof.

Figure 1 is a perspective view of an ash receptacle showing my new design.

Fig. 2 is a plan view of the same.

Fig. 3 is a side elevational view of the same.

I claim:

The ornamental design for a tobacco ash receptacle, substantially as shown.

PHILIP N. SEA.
